Attorney.

United States Patent Office.

JAMES SWAN, OF SEYMOUR, CONNECTICUT.

Letters Patent No. 76,955, dated April 21, 1868.

IMPROVED MACHINE FOR MAKING AUGER-BITS.

The Schedule referred to in these Letters Patent and making part of the same.

TO ALL WHOM IT MAY CONCERN:

Be it known that I, JAMES SWAN, of Seymour, in the county of New Haven, and State of Connecticut, have invented a new and improved Machine for Manufacturing Augers and Bits; and I do hereby declare that the following is a full and exact description thereof, which will enable others skilled in the art to make and use the same, reference being had to the accompanying drawings, and to the letters of reference marked thereon.

This invention consists in a new and improved machine for manufacturing screw-augers and bits, and in a novel arrangement of dies and a clamp, all arranged and operated as hereinafter set forth, whereby bits and augers may be very expeditiously manufactured, and at a moderate cost.

In the accompanying sheet of drawings—

Figure 1 is a vertical section of my invention, taken in the line *xx*, fig. 2.

Figure 2, a plan or top view of the same.

Figure 3, a vertical section of the same, taken in the line *yy*, fig. 2.

Figures 4 and 5, detached views of holding-jaws pertaining to the same.

Figures 6, 7, and 8, views of an auger or bit in process of manufacture.

Similar letters of reference indicate like parts.

A represents the frame of the machine, which may be constructed in any proper manner to support the working parts, and B B represent two parallel shafts, placed in the upper part of said frame, and connected by bevel-gears, C, to a shaft, D, on which a cam, E, is firmly keyed. The power is applied to one of the shafts, B. On each shaft, B, there are secured three cams, F F' F''. The cams F F'' project from their shafts in opposite directions, and the central one, F', being at right angles with the other two.

The cams of the two shafts, which have similar letters, operate in pairs, and simultaneously against slides, G G' G'', all of which are shown in fig. 2, the slides being arranged in pairs, as shown clearly in said figure.

The slides above alluded to are pressed toward each other by the cams, and are thrown back by springs, H, which are shown in fig. 1.

I represents a slide, which is fitted between suitable guides, *a a*, on the frame A, and is shoved forward in the direction indicated by the arrow 1, by the cam E, and thrown back by a spring, b, as shown in fig. 3. On this slide, I, there is firmly secured a jaw, J, a corresponding jaw, J', being attached to a pivoted bar, K, having a lever, L, at its rear end. The jaw J' is directly above J, and the former is brought down upon the latter, by means of a lever, L, arranged as shown in fig. 3. These jaws J J' are made in such a manner as to receive the twisted blank of the auger or bit, and hold it firmly while the cutting-portion of the bit is formed. A face view of these jaws is shown clearly in figs. 4 and 5.

The cutting-portion of the auger or bit is formed by dies at the ends of the slides G G' G''. The dies *c* of the slides G are formed each with three recesses, *d*, as shown in fig. 3, and these dies, when pressed against the end of the auger or bit-blank, form three spurs or projections, *e*, as shown in fig. 6. The dies *f* of the slides G' are formed each with three recesses and four cutting or prominent surfaces, *g*, which cut the burr around and between the spurs or projections *e*, and leave the same in a clean, sharp state, as shown in fig. 7. The dies *h* of the slides G'' are formed with projections, *i*, which bend the end-spurs *e* outward at right angles with the axis of the auger or bit, as shown in fig. 8, and complete the work.

The cam E is of peculiar form or shape, as shown clearly in fig. 3, and has a circular portion, *j*, which is concentric with shaft H. It also has two straight surfaces or edges, *k k*, which are tangential, or about so, with the circular portion *j*. The cam also has two curved edges, *l l'*, one of which, *l'*, is a portion of a circle greater than *l*.

When the slide I is forced fully back, under the influence of the spring *b*, the slide is in contact with the portion *j* of the cam E, and, when the slide is in this position, the twisted blank, properly heated, is placed and gripped between the jaws J J'.

On applying power to one of the shafts, B, motion is communicated to both, and to the shaft D, the cam E

rotating in the direction indicated by arrow 2, and, while said part *j* of the cam is in contact with the slide I, the latter is stationary, and the slides G G are moved toward each other by the cams F F, and the three spurs or projections *e* are formed by the dies *c*, as shown in fig. 6.

The slides G are then moved back by their springs, H, and the slide I is moved forward, in the direction indicated by arrow 1, by one of the straight portions, *h*, of the cam E, and the spurs *e* of the auger or bit are brought in line with the dies *f* of the slides G' G', and the burr around the spurs or projections *e* is trimmed off, as shown in fig. 7, the curved portion *l* retaining the slide I, until the cams F' have completed their work, and the springs H of the slides G' have thrown them back. The portion of the cam E between the two curved portions *l* then throws the slide I still further forward, so that the spurs *e* will be in line with the projections *i* of the dies *h*, and said projections being pressed toward each other by the cams F'', the end-spurs *e* will be bent out at right angles with the axis of the auger or bit, as shown in fig. 8. The slides G'' are then forced back by their spring H, and the slide I forced back by its spring, *b*, another blank placed between the jaws J J', and the operation repeated.

Having thus described my invention, I claim as new, and desire to secure by Letters Patent—

1. The holding-jaws J J', attached to the sliding plate I, in combination with the slides G G' G'', provided with the dies *c f h*, all constructed and arranged to operate in the manner substantially as and for the purpose set forth.
2. The combination of the holder J J', constructed as described, in combination with the operating parts thereof, as herein shown and described.

JAMES SWAN.
